FRANK B. WILDMAN AND GEORGE LAWSON BALLARD, OF NORRISTOWN, PENNSYLVANIA, ASSIGNEES TO WILDMAN MFG. CO., A CORPORATION OF PENNSYLVANIA.

WELT-KNITTING MACHINE.

1,166,289.

Specification of Letters Patent. Patented Dec. 28, 1915.

Application filed June 17, 1912. Serial No. 704,168.

To all whom it may concern:

Be it known that we, FRANK B. WILDMAN and GEORGE LAWSON BALLARD, a citizen of the United States and a subject of the King 5 of Great Britain, respectively, and residents of Norristown, Pennsylvania, have invented certain new and useful Improvements in Welt-Knitting Machines, of which the following is a specification.

10 Our invention relates to that type of latch needle rib knitting machine which is designed to produce tubular welts, and in which a single main thread is used, and an additional thread is thrown in when the 15 welt is to be formed.

Our present invention is an improvement upon that disclosed in Letters Patent of the United States granted to us May 25, 1915, No. 1,140,783.

20 In the accompanying drawings Figure 1 is a plan view of a knitting head embodying our invention; Fig. 2 is a developed view of the cam box of the cylinder needles; Fig. 2' is a detail of one of the cam posts. 25 Fig. 3 is a side view of the additional thread feeder and the thread cutter and clamp. Fig. 4 is a bottom plan view of the thread cutter and clamp. Fig. 5 is a side view of a pattern wheel and lever mechanism for controlling the movements of the 30 needle cams of the needle cylinder and for controlling an additional yarn feed mechanism.

In these drawings, 1 is the main thread 35 guide of usual construction, this being suitably fixed to the dial cap as in ordinary practice to rotate therewith.

2 is the guide for the additional thread, which thread is used for forming the outer 40 wall of the tubular welt. This guide 2 is diametrically opposite the main guide, and consists of the arm 3, pivoted to a bracket 4, mounted to rotate with the cylinder cams said arm being operated to and from the 45 needles to present the thread thereto or remove it therefrom by means similar in some respects to that disclosed in Letters Patent of the United States granted to J. B. Hipwell, #815,167, March 13, 1906, and consisting generally of a star wheel 5 which, when operated by contact with a device on the frame, operates through gearing 6 and a cam shaft 7 to raise the lever or thread 50 guide arm or to allow it to fall under the 55 action of a suitable spring. At 9 is shown

a cutting device for the additional thread, which is operated to sever it when the guide arm is raised, and at 10 is a clamp for holding the severed end of the thread so that when the guide arm is again lowered the 60 thread will be presented to the needles, the clamp insuring proper control of the thread until the needles have taken it.

The star wheel 5 of the additional thread feeder is operated by contact with a controlling pin 11 carried by a plate 12' which is adjusted vertically into and out of line with the star wheel by suitable pattern mechanism (not shown).

One movement of the star wheel will 70 throw the guide arm 2 up and the next action of the star wheel will permit the guide arm to fall to present the thread to the cylinder needles.

The cutter, above mentioned, includes a 75 fixed blade 9 and a movable blade 9' pivoted at 9°, Fig. 4. The movable blade is pressed open by a spring 9° and it is closed to sever the yarn by a rod 9° slidably mounted in the frame of thread feeder and acted 80 on by the lever or arm y', pivoted to the frame of the thread feeder at 9°, its free end being in position to be operated by contact with the pin 11 above mentioned. When the arm y' is swung inwardly by striking 85 the pin 11 the shear blade 9' will operate in conjunction with the fixed blade and the clamping plate 10 which is attached to and moves with the movable blade 9' will engage and clamp the yarn upon the upper surface 90 of the fixed blade over which the clamping blade moves it. When the rod 9° is moved inwardly and the shear and clamp closed to cut and hold the thread, the said parts will be held in this position by the frictional engagement of a detent lever 54 pivoted to the frame and pressed by a spring 55, this spring being sufficient to overcome the tendency of the spring 9°, to open the shear blade and clamp. When however, the 100

thread guide arm 2 is thrown down to introduce the additional thread to the cylinder needles, the detent lever 54 will be operated by one of the pins 56 on the end of the cam shaft which controls the guide arm 2 105 and said detent lever will release the rod 9° and the shears and clamp will then be opened and the thread will now be taken by the cylinder needles.

The cams of the dial consist of a stitch 110

cam 12 and a fixed advancing cam 13, the latter differing from the cam of our previous application in that it is fixed in the present case, or, in other words, it is not operated and plays no part in making the welt on the cylinder needles.

The cams for the cylinder needles consist of the advancing cam *a* which may be termed, for convenience, the first advancing cam, and stitch cam *b*, for the main thread, and a second advancing cam *c* and stitch cam *d*. These cams *c* and *d* are for knitting a welt on the cylinder needles in advance of the clearing course to prevent raveling back. They are also used for making the clearing course when the yarn guide 2 for the additional thread is raised to withdraw the said thread, and they also make the outer wall of the tubular welt on the cylinder needles.

In knitting rib fabric only the main thread feed 1 is used, the cams *a*, *b*, of the cylinder and 13, 12, of the dial coöperating to produce this effect.

When the tubular welt is to be formed, the order of operations is as follows: The yarn guide-finger 2 is lowered, bringing the additional thread in the path of the cylinder needles, this taking place at the point in the circuit of the machine where there are no dial advancing or stitch cams, as will be clear from an inspection of Fig. 1 of the drawing, so that only the cylinder needles will take this additional thread, for which purpose the cam *c* is raised to advance the cylinder needles. This will produce a series of one-course wefts, on this side of the machine, alternating with courses of plain rib knitting produced at the main yarn feed 1. These courses of welt are formed because at this point the dial needles are always drawn in. These welt courses serve to hold the loops from raveling back when the clearing course which precedes the tubular welt is made. This clearing course is made by withdrawing the thread at 2 and allowing the cam *d* to knit off. That is to say, as soon as the additional thread is withdrawn the cams *c* and *d* will cause the stitches to be knitted off at this point, and thus the clearing course will be formed. For this action the cam *c* remains up in the same position to which it was raised in making the cylinder needles take the additional thread when the latter was thrown in for making the welt courses just mentioned above. When a sufficient number of clearing courses have been made, the finger 2 is again thrown into action, and at the same time the cylinder advancing cam *a* on the opposite side of the machine is thrown down out of action, causing the machine to knit on the cylinder needles at one side of the machine, and on the dial needles on the other side, *i. e.*, on the cylinder needles at the additional thread

feed 2, and on the dial needles at the main thread feed 1.

More briefly stated, the complete operation of forming the welt and the clearing and binding courses, preceding it and then resuming rib knitting, is as follows: throwing in the additional thread at the point where there are no knitting cams in the dial; raising the second advancing cam *c* to form with the additional thread a welt course or courses on the cylinder needles at the same time that a rib course or courses are being formed at the main feed which alternate with the said welt courses; withdrawing the additional thread to allow the cylinder needles at the said second advancing cam *c* and stitch cam *d* to knit off for forming clearing courses; throwing the additional thread in again to make the outer wall of the welt with the cams *c* and *d* which have remained up, and depressing the first cylinder advancing cam *a*, to make the inner wall of the tubular welt on the dial needles; lowering the second advancing cam *c* and withdrawing the additional thread to stop the formation of the outer wall of the tubular welt, and finally raising the first advancing cam *a* to resume rib knitting. For throwing the additional thread into action, the star wheel and pin 11 act as above described, and after this thread has been thrown into position to be taken by the needles, the second advancing cam *c* is raised. This is done by a cam disk 14 acting on a pin 15 on the cam post *c*^x of the cam *c*. This cam disk 14 is fixed to a shaft 16 which is geared to a shaft 17. These shafts carry respectively arms 18 and 19 to be struck by the roller 20 on the fixed base of the head, it being understood that the needle cam carriers rotate in the direction of the arrow X. The cam disk 14 has an incline at 14' and when it is rotated in the arrow direction this incline working under the pin 15, will lift the cam *c*. It is rotated in this direction by the arm 19 striking the roller 20. The cam *c* remains up during the formation of the single welt courses, the clearing course and the formation of the outer wall of the tubular welt.

When rib knitting is to be resumed, the cam disk 14 is rotated back by the arm 18 striking the roller 20 to remove the incline 14' from under the pin 15, whereupon the cam *c* will fall, it being pressed down by a spring, not shown, as in ordinary practice. The additional thread is also withdrawn by the star wheel hitting the pin 11.

The first advancing cam *a* is operated by a disk cam 21 having an incline 21' engaging under a pin 22 of the post *a*^x of the cam *a*. The cam disk 21 is operated by an arm 23 striking the roller 20, the said arm being on a shaft 24 geared to the shaft 25 of the cam to which is connected the arm 26 for re-

turning the cam disk to its inactive position when the arm strikes roller 20. This cam *a*, as in the application referred to, and in Letters Patent of the United States #1047355, December 17, 1912, granted to us, is moved down step by step. It is spring pressed downwardly, and when the cam disk is rotated to remove the incline 21' the cam *a* falls until its post is caught by a latch or 10 catch lever 26', which enters a notch in the post, the catch being pressed by a spring 27. This spring acts against a lug on the arm 26' which is an integral part of the latch 26' and turns about the shaft 25 all as in the 15 patent referred to. The cam is now held in its intermediate position until the arm 26' of the catch strikes the pattern disk 20, when the post *a*' is released and the spring thereof forces the cam all the way down out 20 of action for the formation of the inner wall of the tubular welt on the dial needles. The notched post is shown in Fig. 2'.

The arms of the pairs 18, 19, and 23, 26, are in different horizontal planes, as is usual 25 in this type of machine, and the controlling roller 20 is controlled by pattern mechanism which raises it into the different planes, in which these arms lie, for their operation. The stitch cam *b* is operated for the slack 30 and loose course through an arm 28 having studs 28', 28'', to bear on inclines on the head 29 of the post *b*' of the cam *b*, the arm 28 being operated from contact arms 30, 31 which, at proper times, strike the roller 20. 35 The plate carrying the pin 11 for operating the star wheel is also operated vertically by pattern mechanism, not shown, to hit or miss the star wheel.

The cutting and clamping means for the 40 additional thread is substantially the same as that disclosed in the Letters Patent 1,140,783, May 25, 1915, above referred to.

The cams *c* and *d* may be said to perform a three-fold function in our present machine, in that they serve to form the one course welts which precede the clearing course; they form the clearing course when the additional thread is thrown out and they form the outer wall of the tubular 50 welt when the additional thread is again thrown in.

As in the application above referred to, when the stitch cam *d* is in the position shown in full lines, the cylinder needles are 55 retracted far enough to cast off their stitches for the clearing course. When, however, the additional thread is thrown in, the cam *d* is simultaneously lowered to draw sufficient yarn to make stitches. This lowering of the cam *d* at the time the additional thread is drawn into the cylinder needles is effected by a cam at 7' on the shaft of the additional feeder acting on a lever 32 connected with a rock shaft mounted on the frame or 60 bracket of the additional feeder, said shaft

having an arm 24' overlying the stem *d*' of the cam *d* so that it will press the same down at the time the additional thread is thrown in to draw enough yarn to form a stitch.

All of the posts of the cams are spring 70 pressed, the springs of *c* and *a* pressing downwardly while the springs of *d* and *b* press upwardly.

The geared connection between the pairs of shafts 16, 17; 24 and 25 is substantially 75 the same as that shown in the said patent at 49, 50, for the pair of shafts 43, 48', this connection being well known in the prior art.

The pattern mechanism for giving the 80 roller 20 its different positions for operating the various arms mentioned may assume different forms, but as one form we show in Fig. 5 a pattern wheel 33 having cam blocks 85 removably carried thereby. The blocks are marked generally 33'. They are of different height according to the requirements of the work to be produced and they operate the lever 34 which engages the stem 20' of the roller 20. The high blocks raise the lever 34 and the low blocks allow the lever together with the roller 20 to fall by gravity and in this way the roller 20 is adjusted to different levels to operate the various levers controlling the needle cams of the needle cylinder. The lever 34 has a roller 34' against 90 which the pattern blocks bear.

The plate 12' carrying the pin 11 which 95 operates the star wheel is operated by a lever 35 pivoted to the frame at 36 and having one arm engaging with the stem 12' of the pin plate 12' and its other arm arranged to be engaged by pins 36' on the pattern wheel for lifting the said plate, the lever arm having an inclined surface at 37 against which 100 the pins ride. In the operation of this pattern wheel, the starting point is at X. When the low part of block 30'a allows roller 34' and lever 34 to fall and lower the roller 20 this roller will operate the arm or lever 30 105 for the loose course. When block 31'a comes under the roller 34' the arm 31 will be operated to throw out the loose course. When pattern block 19'a is effective arm 19 will be operated by roller 20, and this takes place 110 at the time the additional thread is thrown in for the anti-ravel course, the operation of arm 19 causing the raising of the cylinder cam *c*. Cam block 19' jointly with cam block 18'a elevate the roller 34', which 115 causes the operation of arm 18 and control of needle cam *c*. The next part of the cam block system to act on lever 34 is the low part 19'b which brings roller 20 in position for operating arm 19 and needle cam *c*. 120 At 26'a of the pattern wheel the roller 20 is adjusted in position to operate on arms 26 and 26' of needle cam *a*, for lowering the same, for the formation of the welt on the dial needles. At 18'b of the pattern wheel the 125

At 26'b of the pattern wheel the roller 20 is adjusted in position to operate on arms 26 and 26' of needle cam *a*, for lowering the same, for the formation of the welt on the dial needles. At 18'b of the pattern wheel the 130

arm 18 of the second advancing cam of the cylinder is operated, this being at the time the additional yarn feed is thrown out after which the lower surface 23^a comes below the lever 34 and arm 23 of needle cam *a* will be operated to raise said cam to resume rib-knitting.

We claim as our invention:

1. In a latch needle rib knitting machine, 10 a main thread feed, an additional thread feed, dial cams consisting of a stitch cam and an advancing cam at the main feed, an advancing and a stitch cam in the cylinder adjacent those of the dial for making rib fabric with 15 the main thread, a second advancing cam and a second stitch cam in the cylinder at the additional thread feed opposite the point in the dial where there is no advancing and stitch cam for the additional thread feed, controlling means for throwing the additional feed into operation and means for controlling the cylinder cams to make a welt on the cylinder needles at said additional feed while rib fabric is being made at the main feed, and to subsequently make a welt on the dial needles at the main feed while welt is being made at the additional feed on the cylinder needle and to resume rib knitting.
2. In a latch needle rib knitting machine, 30 a main thread feed, an additional thread feed, dial cams consisting of a stitch cam and a non-adjustable advancing cam at the main feed, an advancing and a stitch cam in the cylinder adjacent those of the dial for making rib fabric with the main thread, a second advancing cam and a second stitch cam in the cylinder at the additional thread feed opposite the point in the dial where there is no advancing and stitch cam for the 35 additional thread feed, controlling means for throwing the additional feed into operation and means for controlling the cylinder cams to make a welt on the cylinder needles at said additional feed while rib fabric is being made at the main feed, and to subsequently make a welt on the dial needles at the main feed while welt is being made at the additional feed on the cylinder needle and to resume rib knitting.
3. In a latch needle rib knitting machine, 50 a main thread feed, an additional thread feed, dial cams consisting of one stitch cam and one advancing cam at the main feed, an advancing and stitch cam in the cylinder adjacent those of the dial for making rib fabric, a second advancing and stitch cam in the cylinder at the additional feed, means for operating the additional thread feed to throw the same in, means for raising the 55 second advancing cam when the additional

thread is thrown in to form a welt course or courses on the cylinder needles, at the same time that a rib course or courses are being formed at the main feed which alternate with said welt courses, said operating 65 means for the additional thread then withdrawing the additional feed to allow the cylinder needles at the second advancing and stitch cam to knit off for forming clearing courses, said operating means for the 70 additional thread then throwing the same in to make one wall of the tubular welt with the additional thread, means for then depressing the first cylinder advancing cam to allow the dial needles to make the other 75 wall of the welt, the operating means for the second advancing cam then lowering the same and the operating means for the additional thread then withdrawing the additional thread to stop the formation of the 80 outer wall of the welt, and the operating means for the first advancing cam then raising the same to resume rib knitting, substantially as described.

4. In a rib-knitting machine, a main 85 thread feed, an additional thread feed, dial cams consisting of one stitch and one advancing cam at the main feed, an advancing cam and a stitch cam for the cylinder needles adjacent those of the dial for making rib fabric, a second advancing cam and a second stitch cam for the cylinder needles at the additional feed, means for throwing in the additional feed, means for raising the second advancing cam when the additional 90 thread is thrown in to form a welt course or courses on the cylinder needles while a rib course or courses are being formed at the main feed, means for subsequently depressing the first cylinder cam to make welt on 95 the dial needles at the main feed while welt is being made at the additional feed on the cylinder needles, the operating means for the second advancing cam then lowering the same and the operating means for the additional thread then withdrawing the same to stop the formation of the welt on the cylinder needles, and the operating means for the first advancing cam then raising the 100 same to resume rib-knitting with the main 105 thread, the said dial cams having a fixed relation to each other for the operations mentioned, substantially as described.

In testimony whereof, we affix our signatures in presence of two witnesses:

FRANK B. WILDMAN.
